CLAIM

The ornamental design for an electronic control housing for a pigment removal tool, as shown and described.

DESCRIPTION

FIG. 1 is a top plan, front and left side perspective view of an electronic pigment removal machine showing my new design; and,

FIG. 2 is a bottom plan, rear and right side perspective view.

The broken line showing of the pigment removal pen in FIG. 1 is for illustrative purposes only and forms no part of the claimed design.

FIG. 1

FIG. 2
